Norman J. Holland
ATTORNEY

UNITED STATES PATENT OFFICE

HAROLD J. CARR, OF NEW YORK, N. Y., ASSIGNOR TO ANCHOR CAP & CLOSURE CORPORATION, OF LONG ISLAND CITY, NEW YORK, A CORPORATION OF NEW YORK

SCREW CAP

Application filed March 18, 1927. Serial No. 178,308.

The present invention relates to closure caps and more particularly to a screw cap having portions adapted to be deformed to facilitate removal thereof.

One of the difficulties encountered in the use of screw caps is their tendency to adhere to the threads of containers thereby preventing ready removal. The mechanical devices which have been developed for unscrewing the caps, usually comprise a band which encircles the cap together with an arm extending laterally therefrom to which pressure may be applied to rotate the cap. The contraction of the band about the cap increases as pressure is applied. This squeezes the skirt of the cap against the container but the leverage afforded by the laterally extending arm permits the necessary force to be applied to detach the cap. Frequently breakage occurs and the operator is subjected to the danger of being injured by the broken glass.

Then too, many consumers do not have the necessary opening devices for screw caps and resort to tapping the outer edge of the cover to loosen it. This is even more dangerous due to the fact that small pieces of glass may be chipped from the mouth or the container and lodge in the food without being noticed. Caps have been formed with annular beads or bulges intermediate the skirt and cover portion to permit tapping without breakage. This expediency is likewise unsatisfactory.

The present invention overcomes these difficulties by minimizing the tendency of the cap to adhere to the container and by providing in addition an effective means for overcoming any tendency of the cap to stick when it is desired to remove it.

An object of the invention is to minimize the tendency of a screw cap to adhere to a container; and to provide an effective means of overcoming any tendency of the cap to stick.

Another object of the invention is to minimize the breakage of the containers occasioned by the removal of screw caps by present appliances.

A further object of the invention is to

facilitate the removal of a screw cap by expanding the skirt in a circumferential direction so that it may be detached without difficulty.

Other and further objects of the invention will be obvious upon an understanding of the illustrated embodiment about to be described; and various advantages not referred to herein will occur to one skilled in the art upon employment of the invention in practice.

In accordance with these objects, the preferred form of cap is provided with an interrupted thread formed by spirally arranged projections which, if joined together, would form a continuous thread. In this way the surface of the cap in contact with the container is reduced to a minimum and the chance of the formation of rust is not so great. Further, the formation of rust, if any, exists on a small area and the tendency to resist detachment may be readily overcome.

A series of vertical ribs are provided intermediate the thread engaging projection. These ribs not only facilitate gripping of the container manually or by means of an appliance, but they also form outwardly extending projections which may be deformed or flattened to expand the skirt of the cap circumferentially and loosen same upon the container. Tapping in either a circumferential or radial direction is very effective as a means of loosening the cap. Since the tapping or pressure for deforming the ribs is at substantially the center of the skirt and not at the top thereof, there is little danger of chipping the glass container. If the usual mechanical appliance is applied to such a cap, the constriction of the band fitting about the cap, instead of binding the cap against the threads, will depress the ribs and expand the cap so that it will release its hold on the threads.

A preferred embodiment of the invention has been chosen for purposes of illustration and description and is shown in the accompanying drawings, wherein

Fig. 1 is a side elevational view of the closure; 100

Fig. 2 is a top plan view of the closure;
Fig. 3 is a vertical sectional view of the closure;

Fig. 4 is a horizontal sectional view 5 through the cap along the line 4—4 of Fig. 1;

Fig. 5 is a side elevational view of the closure applied to a container;

Fig. 6 is a sectional view of the closure applied to a container, the container being 10 shown in elevation;

Fig. 7 is a fragmentary sectional view illustrating the vertical rib in its normal condition; and

Fig. 8 is a fragmentary sectional view 15 showing the vertical rib slightly flattened.

Referring to the drawings, there is shown a closure cap having a cover portion 1 and a depending skirt 2 with its lower edge rolled to form a bead or wire edge 4. A series of 20 projections 5 are arranged circumferentially of the skirt in the form of a spiral, whereby if the ends of the respective projections were joined, a continuous thread would be formed. In this way the projections will engage the 25 continuous threads 6 on the container 7. It will be understood that the projections 5 may be of any desired length. The liner or gasket 8 may be fitted in the upper portion of the cap to form an edge seal in the usual 30 manner. The projections being canted slightly to the cover portion of the cap engage throughout their length the respective threads on the container and furnish a 35 strong locking lug. The wire edge 4 strengthens the bottom of the skirt thereby preventing the cap from expanding during application. The wire edge also improves the appearance of the cap. The upper portion of the skirt of the cap may be knurled 40 as shown at 3 to improve its appearance and to strengthen this portion of the skirt.

Intermediate the thread engaging projections 5, which preferably are four in number, are a series of vertical ribs 9. While 45 these ribs or projections may be of any desired shape they are here shown extending substantially the entire width of the skirt pressed outwardly from the plane of the skirt to facilitate tapping or otherwise flattening to expand the skirt of the cap. This 50 form of rib likewise has the advantage of strengthening the skirt in a vertical direction and also facilitates manual gripping or the attachment of a suitable mechanical device 55 for removing the cap. In the case of the usual device, the gripping band will squeeze the projections 9 and instead of constricting and binding the cap about the container it 60 will actually depress the ribs to loosen the cap thereon. This is illustrated in Figs. 7 and 8. It will be noted that in Fig. 8 where the rib is shown flattened the skirt of the cap is enlarged and fits loosely upon the container. These laterally protruding ribs also

permit tapping in a circumferential direction to jar the cap loose if necessary.

The cover portion of the cap is provided with arcuate panels 11 which improve the appearance of the cap and also increase the 70 rigidity of the cover portion thereof. Preferably these panels are four in number and are arranged adjacent the thread engaging projections 5 with the gaps 12 between their ends adjacent the vertical ribs 9. 75

In removing the cap from a container the ribs 9 may be flattened by pressure upon a flat object or by tapping with a suitable device to expand the skirt in a circumferential direction. Thereafter the cap may be rotated without difficulty from the container. If desired, the projections 9 may be tapped in a circumferential direction to jar it loose and to initiate its rotative movement. 80

It will be seen that the present invention 85 provides an inexpensive screw cap readily applicable to commercial containers. The relatively short thread engaging lugs prevent adherence of the cap to the container and the vertical ribs permit expansion of the 90 skirt to loosen it or tapping of the skirt in a circumferential direction to initiate the rotative movement of the cap for its removal.

It will be understood that the shape of the 95 thread engaging projections may be materially changed without departing from the scope of the invention and it will also be understood that features of the invention are equally applicable to closure caps having lugs suitable for application to containers 100 having interrupted threads. Various other changes may be made and it is therefore desired that the above description be taken as 105 illustrative and not in a limiting sense.

Having thus described my invention, I 105 claim:

1. As an article of manufacture, a closure cap comprising thread engaging lugs spirally disposed in the skirt thereof, outwardly extending projections intermediate 110 said lugs adapted to be flattened to increase the circumferential size of the cap, thereby to facilitate removal of said cap from a container.

2. As an article of manufacture, a screw 115 cap comprising a cover portion, a depending skirt, an interrupted thread formed by circumferential projections spirally arranged in the skirt of said cap, and outwardly extending projections intermediate said circumferential projections adapted to be flattened to increase the circumferential length between projections thereby to facilitate the removal of said cap from a container.

3. As an article of manufacture, a screw 125 cap adapted to be applied to a continuous thread container comprising a cover portion, a depending skirt, a plurality of inwardly extending thread engaging projections spirally arranged, and a plurality of outward- 130

ly extending vertical ribs intermediate said projections adapted to be flattened to facilitate removal of said cap.

4. As an article of manufacture, a screw cap adapted to be applied to a continuous thread container comprising a cover portion, a depending skirt, a series of projections spirally arranged in the skirt of the cap adapted to engage screw threads on a container, and vertical ribs extending transversely of said skirt adapted to be flattened to expand the skirt circumferentially thereby to facilitate removal of said cap from the container.

5. As an article of manufacture, a screw cap adapted to be applied to a continuous thread container comprising a cover portion, a depending skirt, a rolled edge at the bottom of said skirt, a series of thread engaging projections extending circumferentially and spirally of said skirt, said projections being formed by pressing inwardly the metal in a continuous skirt, and a plurality of projections intermediate said thread engaging projections adapted to be deformed to facilitate removal of said cap.

6. A sealed package comprising a container having a continuous thread thereon, a closure cap having a cover portion and a depending skirt, a rolled edge at the bottom of the skirt, corrugations at the top of the skirt, spirally arranged projections in the skirt of the cap intermediate the rolled edge and the corrugations adapted to engage the thread on the container, and vertically disposed, outwardly extending projections intermediate said spiral projections extending substantially the entire length of the skirt.

7. A sealed package comprising a container having a continuous thread thereon, a closure cap having a cover portion and a depending skirt, a rolled edge at the bottom of the skirt, corrugations at the top of the skirt, spirally arranged projections in the skirt of the cap intermediate the rolled edge and the corrugations adapted to engage the thread on the container, said projections being formed by pressing inwardly the metal of the skirt without interrupting the continuity of the skirt, and vertically disposed, outwardly extending projections intermediate said spiral projections extending substantially the entire length of the skirt, said vertical projections being adapted to be flattened to facilitate removal of the cap from the container.

HAROLD J. CARR.
